United States Patent Office.

GEORGE HARTJE AND LUCIEN S. JACQUIN, OF NEW YORK, N. Y.

Design No. 3,411, dated March 23, 1869.

DESIGN FOR A LOCKET.

The Schedule referred to in these Letters Patent and making part of the same.

To all whom it may concern:

Be it known that we, GEORGE HARTJE and LUCIEN S. JACQUIN, of New York, in the county of New York, and State of New York, have invented a new and original Design for a Locket; and we do hereby declare that the following is a full, clear, and exact description thereof, which will enable others skilled in the art to make and use the same, reference being had to the accompanying drawings, forming part of this specification.

Figure 1 is a side view of our improved locket.

Figure 2 is an edge view of the same.

Figure 3 is a cross-section of the same.

Similar letters of reference indicate corresponding parts.

My invention has for its object to furnish an improved design for a locket; and

It consists in the design hereinafter more fully described.

A represents the locket, which is made oval in its general form.

The sides of the locket are made slightly convex, as shown in fig. 3.

The edges of the two parts of the locket are turned over, as shown in fig. 2, so as to give it the appearance of being beaded with a double beading around its edge.

The eye a' , by means of which the locket is suspended, is attached to one end of said locket, as shown in figs. 1 and 2.

What we claim as our invention, and desire to secure by Letters Patent, is—

The design for a locket, herein set forth.

The above specification of our invention, signed by us, this 20th day of February, 1869.

GEO. HARTJE.
LUCIEN S. JACQUIN.
